DESIGN FOR A BLOUSE

Irving Geist, New York, N. Y.

Application October 9, 1935, Serial No. 58,890

Term of patent 3½ years

To all whom it may concern:

Be it known that I, Irving Geist, a citizen of the United States of America, residing in Manhattan, county of New York, and State of New York, have invented a new, original, and ornamental Design for a Blouse, of which the following is a specification, reference being had to the accompanying drawing, forming part thereof, wherein,

The superimposed cording as indicated by parallel lines, commences at the cuff of the sleeve and runs continuously up the sleeve, over the neckline and down the opposite sleeve.

I claim:

The ornamental design for a blouse, substantially as shown, and described.

IRVING GEIST.
